Attorney, Agent, or Firm—Wolf, Greenfield & Sacks[57] **CLAIM**

The ornamental design of an arm float, as shown and described.

DESCRIPTION

FIG. 1 is a left rear perspective view of one embodiment of an arm float, showing a new design;

FIG. 2 is a right side perspective view thereof;

FIG. 3 is a rear elevational view thereof;

FIG. 4 is a front elevational view thereof;

FIG. 5 is a right side elevational view thereof, with the left side elevation being a mirror image;

FIG. 6 is a top plan view thereof, with the bottom plan view being a mirror image;

FIG. 7 is a right side perspective view of a second embodiment of an arm float, showing a new design;

FIG. 8 is a left side elevational view thereof, with the right side elevation being a mirror image;

FIG. 9 is a right front perspective view thereof;

FIG. 10 is a front elevational view thereof;

FIG. 11 is a rear elevational view thereof; and,

FIG. 12 is a top plan view thereof, with the bottom plan view being a mirror image.
